SIGN HOLDER

Philip Hopp, New York, N.Y., assignor to The Hopp Press, Inc., New York, N.Y., a corporation of New York

Filed Aug. 1, 1966, Ser. No. 3,303

Term of patent 14 years

(Cl. D1—3)

FIG. 2

FIG. 3

FIG. 4

FIG. 5

FIG. 1 is a perspective view of a sign holder showing my new design;

FIG. 2 is a top plan view thereof;

FIG. 3 is an elevational view taken from the side opposite that shown in FIG. 1;

FIG. 4 is an elevational view taken from one end thereof; and

FIG. 5 is a bottom plan view thereof.

The fragmentary broken line representation of a price tag's moulding and the broken line representation of a sign card in FIG. 1 are for purposes of illustration only.

I claim:

The ornamental design for a sign holder, substantially as shown and described.
